DESIGN FOR A BATHTUB

Norman A. Hesler, Sackville, New Brunswick,
Canada

Application January 8, 1934, Serial No. 50,355

Term of patent 14 years

To all whom it may concern:

Be it known that I, NORMAN A. HESLER, a subject of the King of Great Britain, residing at the town of Sackville, in the county of Westmoreland, Province of New Brunswick, Canada, have invented a new, original, and ornamental Design for Bath Tubs, of which the following is a specification, reference being had to the accompanying drawing, forming part thereof.

The figure is a perspective view of a bath tub, showing my new design.

The contour of the bath tub is conventional.

I claim:

The ornamental design for a bath tub substantially as shown and described.

NORMAN A. HESLER.
